UNITED STATES PATENT OFFICE.

EUGENE HIGGINS, OF JACKSON, MICHIGAN, ASSIGNOR TO HAYES WHEEL COMPANY,
OF JACKSON, MICHIGAN.

ROLLING MACHINE.

Application filed April 23, 1924. Serial No. 708,459.

To all whom it may concern:

Be it known that I, EUGENE HIGGINS, a citizen of the United States, residing at the city and county of Jackson, State of Michigan, have invented certain new and useful Improvements in Rolling Machines, of which the following is a specification.

This invention relates to improvements in rolling machines for automobile wheel rims 10 or machines of that character.

In the formation of automobile rims, it is necessary to bring the rolls gradually but positively together in order to permit the metal to spin or roll into the forms desired 15 and at the same time it is desirable to permit the rolls to be quickly separated after their work is performed to facilitate the operation of the machine.

It is the object of this invention to provide an improved rolling machine with improved control means for that purpose.

Objects pertaining to details and economies of construction and operation will appear from the detailed description to follow.

I accomplish the objects of this invention by the mechanism described in the following specification. The invention is clearly defined and pointed out in the claims.

A machine which is a preferred embodiment of my invention is illustrated in the accompanying drawing forming a part of this application, in which:

Fig. I is a detail side elevation view of a rolling machine embodying the features of my invention.

Fig. II is an enlarged vertical transverse sectional elevation view, parts being shown in full lines, taken on the irregular line 2—2 of Fig. I.

Fig. III is an enlarged detail sectional view of the inlet and check valve for the oil cylinder of the dash pot control means taken on line 3—3 of Fig. II.

Fig. IV is a detail sectional view on line 4—4 of Fig. I, showing the connection of the pitmen from the cross head to the rock shaft for raising the movable roll into working position, the same appearing in the down position.

In the drawing similar reference characters refer to similar parts throughout the several views, and the sectional views are taken looking in the direction of the little arrows at the ends of the section lines. The

parts of the drawing will be referred to by their numbers.

The main frame is made up of sides 1 and 2 connected together by a frame casting 3 integral with which is formed the engine cylinder 4 for control.

The base 5 for the driving motor and gear is bolted to the frame member 2 and carries electric motor 6 driving the gear 7 by a pinion 8 which drives shaft 9 carrying suitable gears 10 for driving the main gear 11 (see Fig. II) on the main roll shaft 12 of the machine which carries the upper fixed roll 13.

The movable roll 14 is carried on shaft 15 which is journaled on slide 16 which travels in ways 17 to and from the main roll. This shaft is driven by the train of gears 18, 19, 20 and 21 from the driving gear 12' on the main roll shaft to the driven gear 15' on the movable roll shaft 15. Gear 21 of the train is carried on the rocker 22 which is pivoted coaxially with the gear 20 so that it rocks in mesh with the gear 20 and follows the movements of the gear 15' to drive the same when it is moved to and from its working position.

The rocker 22 is secured by any suitable means to the slide so that it can oscillate therewith or its relation may be maintained in any way to insure the meshing of the gear 21 with the gear 15'.

The roll slide is actuated from the rock shaft 23 carrying the rock shaft arm 24 which connects by pitmen 25 to the said slide, there being a pitman at each end of the slide.

The rock shaft is actuated from the cross head 26 which is connected by a pitman 27 to the rock shaft arm 28 on the said rock shaft 23. This cross head is reciprocated from the engine comprising cylinder 29 containing piston 30. Air, preferably though other motor fluid may be provided, is introduced to the engine cylinder through any throttle means indicated diagrammatically by the connection 40. The engine movements are controlled by a dash pot comprising the piston plunger 31 reciprocated in the cylinder 32. This dash pot is supplied with oil from a tank 33, the oil being admitted past the inwardly opening spring seated self-closing inlet valve 34 maintained in position against the valve seat 36 by a spring

35. The oil reservoir 33 has an auxiliary chamber 37 extending down by the side of the dash pot control cylinder 32.

A series of discharge ports 38 connect the cylinder of the dash pot at intervals for a considerable portion of its length to the auxiliary chamber. These ports are controlled by the separately adjustable needle valves 39 carried in the wall 37' of the auxiliary reservoir extension 37. These parts are at different distances from the end of the cylinder and are covered and uncovered successively by the plunger piston.

From this description it will be seen that 15 when the machine is thrown into operation, the rolls will be suitably driven and they are, of course, preferably provided with compensating driving means.

The rim to be rolled is inserted in place 20 and the rolls are in action and air is admitted to the cylinder 29. This forces through its cross head and rock shaft connections the movable roll shaft and its roll into work and the rate of its advance is controlled by the 25 discharge of oil in the dash pot past the series of needle valves into the oil reservoir. The resistance to this movement gradually increases as the plunger passes the ports 38 in the side of the cylinder until its final 30 movement which is very slow owing to the slow rate at which the oil passes the last needle valve into the reservoir. This insures the gradual event movement of the roll to its work and permits and insures the 35 spinning of the parts effectively. When the engine is reversed or released, its weight when it is returned by gravity, permits it to drop quickly to the starting position, the large inlet valve 34 is raised from its seat 40 35 and the oil rushes in from the reservoir to fill the dash pot cylinder ready for the next operation.

I have shown this improved means in connection with a rolling machine but it can be 45 applied to control the movements of rolls generally although it is specially adapted for the particular machine and work here shown in its special connections and relations.

50 I desire to claim the invention specifically as shown, and also broadly as pointed out in the appended claims.

Having thus described my invention, what I claim as new and desire to secure by Letters Patent, is:

1. In a rolling machine, the combination of a frame, a roll upon a fixed shaft, a movable roll upon a shaft supported in a slide, a driving means and a gear train between 60 the said rolls for driving the same in unison, a rock shaft with rock arms and connections for actuating the said slide, an engine with cross head and link connections therefrom to actuate the said rock shaft, a dash pot 65 comprising a plunger secured to the said

cross head and a cylinder with an oil reservoir therefor having an auxiliary extension to one side of the said cylinder, a series of exhaust ports in the dash pot cylinder leading to the oil reservoir and adjustable valves 70 for controlling the said ports to regulate the same, and a spring seated yielding intake valve between the oil reservoir and the dash pot cylinder to permit the quick return of the machine and the filling of the said dash pot cylinder with oil, coacting as specified.

2. In a rolling machine, the combination of a frame, a roll upon a fixed shaft, a movable roll upon a shaft supported in a slide, a driving means and a gear train between 80 the said rolls for driving the same in unison, a rock shaft with rock arms and connections for actuating the said slide, an engine with cross head and link connections therefrom to actuate the said rock shaft, a dash pot comprising a plunger secured to the said cross head and a cylinder with an oil reservoir 85 therefor having an auxiliary extension to one side of the said cylinder, a series of exhaust ports in the dash pot cylinder leading to the oil reservoir, and a spring seated yielding intake valve between the oil reservoir and the dash pot cylinder to permit the quick return of the machine and the filling of the said dash pot cylinder with oil, coact- 90 ing as specified.

3. In a rolling machine, the combination of a frame, a roll upon a fixed shaft, a movable roll upon a shaft supported in a slide, a driving means and a gear train between 100 the said rolls for driving the same in unison, a rock shaft with rock arms and connections for actuating the said slide, an engine with cross head and connections therefrom to actuate the said rock shaft, a dash pot comprising a plunger secured to the said cross head and a cylinder with an oil reservoir 105 therefor having an auxiliary extension to one side of the said cylinder, a series of exhaust ports in the dash pot cylinder leading to the oil reservoir and adjustable valves for controlling the said ports to regulate the same, and an intake valve between the oil reservoir and the dash pot cylinder to permit the quick return of the machine and the filling of the said dash pot cylinder with oil, coacting as specified.

4. In a rolling machine, the combination of a frame, a roll upon a fixed shaft, a movable roll upon a shaft supported in a slide, a 110 driving means and a gear train between the said rolls for driving the same in unison, a rock shaft with rock arms and connections for actuating the said slide, an engine with cross head and link connections therefrom to actuate the said rock shaft, a dash pot 115 comprising a plunger secured to the said cross head and a cylinder with an oil reservoir therefor having an auxiliary extension to one side of the said cylinders, a 120

125

130

series of exhaust ports in the dash pot cylinder leading to the oil reservoir, and an intake valve between the oil reservoir and the dash pot cylinder to permit the quick return of the machine and the filling of the said dash pot cylinder with oil, coating as specified.

5. In a rolling machine, the combination with a supporting frame, of a roll upon a fixed shaft, a movable roll, an engine connected to control the said movable roll, a dash pot connected to the said engine comprising a plunger and a cylinder with an oil reservoir having an auxiliary extension to one side of the said cylinder, a series of 10 exhaust ports with adjustable valves leading from the said dash pot cylinder to the said reservoir, and a valved opening from the said reservoir to the cylinder to permit the quick return and fill the dash pot cylinder with 15 oil.

6. In a rolling machine, the combination with a supporting frame, of a roll upon a fixed shaft, a movable roll, an engine connected to control the said movable roll, a dash pot connected to the said engine comprising a plunger and a cylinder with an oil 20 reservoir having an auxiliary extension to 25

one side of the said cylinder, a series of exhaust ports leading from the said dash pot cylinder to the said reservoir, and a valved opening from the said reservoir to the cylinder to permit the quick return and fill the dash pot cylinder with oil.

7. In a rolling machine, the combination with a supporting frame, of a roll upon a fixed shaft, a movable roll, an engine connected to control the said movable roll, a dash pot connected to the said engine comprising a plunger and a cylinder with an oil supply, and a series of exhaust ports with 30 35 adjustable valves leading from the said dash pot cylinder.

8. In a rolling machine, the combination with a supporting frame, of a roll upon a fixed shaft, a movable roll, an engine connected to control the said movable roll, a dash pot connected to the said engine comprising a plunger and a cylinder with an oil supply, and a series of exhaust ports leading 40 45 from the said dash pot cylinder.

In witness whereof I have hereunto set my hand.

EUGENE HIGGINS.
